UNITED STATES PATENT OFFICE.

AARON H. WOLFF, OF NEW YORK, N. Y.

DESIGN FOR A GAS-HEATER.

45,214.

Specification for Design.

Patented Feb. 3, 1914.

Application filed October 28, 1913. Serial No. 797,909. Term of patent 7 years.

To all whom it may concern:

Be it known that I, AARON H. WOLFF, a citizen of the United States, and resident of the city of New York, in the county of New York and State of New York, have invented a new, original, and ornamental Design for Gas-Heaters, of which the following is a specification, reference being had to the accompanying drawing, forming part thereof.

The figure shows a general view of the gas heater illustrating my design.

The essential features of my design consist in a four sided vertically-elongated polygonal casing mounted on four legs and having a dome and a crown at the top.

In the drawing, 1 represents one of the four sides of the casing, and 2 represents a panel in the side which is semicircular at its upper part 3. In the upper part of the panel is a semicircular arrangement of openings 4, 5.

6 represents a convex post at each corner, 7 is a convex base at each side, and 8 are the supporting legs of the casing. On top of the casing is an angular gently curving dome 9, having four sides 10 with leaves 11 at each corner. On top of the dome is a four sided convex crown 12 with elongated openings 13 and a knob 14.

What I claim is—

The ornamental design for a gas heater, substantially as shown and described.

Signed at the city of New York, in the county of New York and State of New York, this 27th day of October, A. D. 1913.

AARON H. WOLFF.
